UNITED STATES PATENT OFFICE.

EDWARD DAVIS, OF BOSTON, MASSACHUSETTS, ASSIGNOR TO MEYER A. BERNHEIMER AND RALPH W. GORDON, OF NEW YORK, N. Y.

ELECTRICAL TIME-RECORDER.

SPECIFICATION forming part of Letters Patent No. 652,753, dated July 3, 1900.

Application filed June 12, 1899. Serial No. 720,163. (No model.)

To all whom it may concern:

Be it known that I, EDWARD DAVIS, of Boston, in the county of Suffolk and State of Massachusetts, have invented certain new and 5 useful Improvements in Electrical Time-Recorders, of which the following is a specification.

This invention has for its object to provide an improved mechanism for printing on the 10 tape of a recording instrument, such as the recorder of a police-signaling or other system, the time of receiving a message.

The invention consists in the novel features of construction and arrangement which I 15 shall now proceed to describe and claim.

Of the accompanying drawings, Figure 1 represents a top plan view of a time-recording instrument constructed in accordance with my invention. Fig. 2 represents a reverse plan view thereof. Fig. 3 represents an elevation of one end of the mechanism with portions broken away. Fig. 4 represents a side elevation. Fig. 5 represents an elevation of the other end of the mechanism. Fig. 6 represents a section on line 6 6 of Fig. 4. Fig. 7 represents a section on line 7 7 of Fig. 4. Fig. 8 represents an end elevation showing a modification. Fig. 9 represents a view of the back of the clock, showing the 25 mechanism carried thereby. Fig. 10 represents a section on line 10 10, Fig. 9. Fig. 11 represents a diagrammatic view of the circuits. Fig. 12 represents a detail horizontal section taken below the upper frame-plate and showing the retarding-escapement.

The same reference characters indicate the same parts in all the figures.

Referring to the drawings, *a* is a horizontal base, on the upper side of which, at one end, 40 are secured standards *a' a'*, forming a framework in which is journaled a shaft *b*, having a type-wheel *c* secured to it and a second type-wheel *d*, of equal diameter, mounted loosely on it alongside the type-wheel *c*. Also 45 affixed to the shaft *b* are a bevel gear-wheel *b'* and a cam *b²*.

Secured to the hub of the loosely-mounted type-wheel *d* is a toothed or ratchet wheel *d'*, engaged by a pawl *d²*, pivotally mounted on 50 the upper end of an arm *d³*. A spring *d⁴*, secured to the arm *d³*, holds the pawl *d²* in en-

gagement with the toothed wheel *d'*, and a spring *d⁵*, attached to said arm and to the framework *a'*, holds a stud *d⁶* on the arm yieldingly against the cam *b²*. An adjustment is provided at *d⁷* for varying the position of the stud *d⁶* on its arm *d³*, and another adjustment is provided at *d⁸* for varying the tension of the spring *d⁵*. As the shaft *b*, carrying the type-wheel *c*, is rotated the edge 60 of the cam *b²*, operating against the stud *d⁶*, retracts the arm *d³* and its pawl, thereby causing said pawl to engage one of the teeth of the wheel *d'*, and when the highest part of the cam has passed the stud *d⁶* the spring *d⁵* 65 returns the arm *d³* and the pawl *d²* propels the toothed wheel *d'* ahead the distance of one tooth, thereby rotating the loosely-mounted type-wheel *d* an equal amount.

The type-wheel *d* has figures cut on its 70 periphery from "1" to "24," indicating the twenty-four hours of the day, and the type-wheel *c* has figures on its periphery indicating the minutes of the hour. A suitable number, as twenty, of divisions are provided on 75 the type-wheel *c*. With twenty divisions the intervals marked by said wheel would be three minutes apart. When the minute type-wheel *c* has made a complete rotation, the hour type-wheel *d* is stepped ahead by the mechanism 80 described a distance of one of its divisions, the toothed wheel *d'* having twenty-four teeth on its periphery.

e represents a plunger mounted to reciprocate in a tubular socket *e'*, affixed to the under side of the base *a*, said plunger carrying at its upper end, above the base, an impression block or platen *e²*. An inking-ribbon *f*, having its ends wound on suitably-journalized rolls *f' f'* and passing around guide-rolls *f²* 90 *f²*, extends between the type-wheels *c d* and the platen-block *e²*. The tape *T*, which runs from or to the recording instrument or other apparatus, passes between the platen-block *e²* and the inking-ribbon *f*, as seen in Figs. 5 95 and 6, and is adapted to receive an imprint from the type-wheels *c d* when the platen-block is elevated to press the tape and inking-ribbon against said type-wheels. Below the base *a* is mounted in a vertical position an 100 electromagnet *g*, whose armature *g'* is secured to a pivotal arm *g²*, supporting the plunger *e*.

The arm g^2 is normally supported by an adjustable stop g^3 in the position represented in Fig. 4; but when the magnet g is energized by an electric current said arm is oscillated, owing to the attraction by the magnet of its armature, and the platen-block e^2 is accordingly projected upwardly against the type-wheels. The rotation of the ink-ribbon rolls f^1 can be effected manually by turning milled heads $f^3 f^8$ on the ends of their shafts, or it can be performed automatically by the mechanism illustrated in Fig. 8, which shows ratchet-wheels $f^4 f^4$ on the shafts f^5 of the ink-ribbon rollers and a pawl f^6 , attached to the upper end of a pivotal lever f^7 , oscillated intermittently by means of pins $f^8 f^8$, attached to the spokes of the type-wheel c , said lever being retracted by means of a spring f^9 and the pawl f^6 having a double-hooked end adapted to engage the teeth on either of the ratchet-wheels f^5 , whereby the pawl rotates said ratchet-wheel step by step and advances the tape in either direction. When the tape has been wound up on one roll and unwound from the other, the operation is reversed by throwing the pawl f^6 into engagement with the opposite ratchet-wheel.

The bevel-gear b' on the end of the type-wheel shaft b is engaged by a bevel-pinion h' , attached to the upper end of a shaft or arbor h . Said arbor passes vertically through the base a and is journaled at its upper end therein, and at its lower end in a plate a^2 , located below the base a and attached thereto by posts $a^3 a^3$. Attached to the arbor h , between the base a and the plate a^2 , is an escape-wheel h^2 , which forms part of a clock-train operated by a spring h^3 . At the lower end of the arbor h is secured a wheel h^4 , composed of insulating material and having a number of pins $h^5 h^5$ placed in a circular series around its periphery.

h^6 is a detent secured to the pivotal armature i of a magnet i and having two stops 2 45 3, adapted to come into engagement with the pins $h^5 h^5$ from opposite sides of their path. The stop 3 is located in advance of the stop 2 and is separated therefrom by a space wide enough to permit the passage of a pin h^5 . Normally the escapement formed by the pin-wheel and the detent is positioned, as represented in Fig. 2, with the stop 2 in the path of the pins h^5 , the force of the spring i^2 in the clock-train holding one of the pins in engagement with said stop, as represented. When the magnet i is energized by the passage of a current, it attracts its armature against the force of a spring i^2 and draws the stop 3 into the path of the pin. The pin-wheel advances a slight distance to bring its pin against said stop 3, and when the armature i^2 is released by a break in the circuit of the magnet i the spring i^2 brings the detent back into its normal position, the pin h^5 escapes through the space between the stops 2 and 3, and the next succeeding pin comes

into engagement with the stop 2. In the arrangement shown the pin-wheel h^4 has five pins h^5 , arranged at equal distances in a circle and the gear-wheels h' and b' are in the ratio 70 of one to four, so that the escape of one pin h^5 on the pin-wheel causes the rotation of the minute type-wheel c a distance equal to one-twentieth of its circumference. The movement of the type-wheel and clock-train during the escape of the pin-wheel h^4 is retarded by means of a retarder included in the clock-train and consisting of a fly or vane h^7 , having a pallet h^8 on its arbor engaging the escape-wheel h^2 .

One terminal i^3 of the winding of the magnet i is connected with a binding-post j , mounted on an insulating-block k on the base a . A second binding-post j' , mounted on said block, is connected with an upwardly-projecting hollow contact post or socket m' , mounted on the base. The other terminal i^4 of the magnet is connected with a second hollow contact post or socket m on the block. The sockets $m m'$ are adapted to receive two 90 metallic studs or contact-posts $m^2 m^3$, attached to the back of a clock o , whereby the clock is separately connected with said sockets. The stud m^3 is electrically connected with the metal work of the clock o , while the stud m^2 is mounted on a plate p of insulating material secured to the back of the clock and is electrically connected with two brushes $q' q$, which embrace the hub of a metal pinion q . The teeth of said pinion mesh with the 100 teeth of two mutilated gear-disks $r s$, secured to an arbor r' , journaled on the plate p . Said arbor has a pinion r^2 on its lower end meshing with a pinion r^3 , secured to the center arbor r^4 of the clock o , said arbor carrying the minute-hand r^5 of the clock. The gear r has every other tooth removed from its periphery, so that in revolving with the pinion q there will be a period of contact between said gear and the pinion and a period of non-contact, thus causing a series of "makes" and "breaks" in an electric circuit which includes the gear and pinion. The gear s is insulated from the gear r and is supplemental thereto, acting to rotate the pinion q when the teeth of the gear r are out of mesh with the teeth of said pinion. The gear s has every other tooth removed from its periphery, but is placed so that its teeth alternate with the teeth of the gear r , the two being therefore mechanically 115 equivalent to a complete gear. The teeth of the gear r are twenty in number, so that in the course of one revolution of the gear twenty makes and twenty breaks are made in the electric circuit. The pinions $r^2 r^3$ are of 120 equal size, so that the revolution of the gear r takes place in one hour when the clock o is running. By virtue of the described connection of the clock with the contact-posts $m m'$ the gear r and pinion q are included in a circuit with the terminals of the magnet i . A battery t or other source of electric energy is 130

interposed in said circuit, as illustrated in Fig. 11. It is accordingly evident that at intervals of three minutes the magnet *i* will be energized and then deenergized, attracting 5 and releasing its armature and operating the pin-wheel escapement, which causes a step-by-step progression of the minute type-wheel *c* at intervals of three minutes and the progression of the hour type-wheel *d* at intervals 10 of an hour.

The receiving instrument, which records the message on the tape, will preferably be placed close to the time-recorder, so that the tape passes from one instrument into the 15 other. The terminals of the printing-magnet *g* may be connected with a suitable contact device in the said receiving instrument, so that upon the receipt of a message said magnet will be energized and the platen-block *e*² 20 elevated, so as to imprint the time of the receipt of the message upon the tape.

The operation, briefly stated, is as follows: The contact-wheel *s* on the back of the clock having twenty teeth and twenty spaces lacking teeth in its circumference and completing one rotation regularly in an hour's time, there will be approximately-equal periods of current and no current through the magnet *i*, each lasting a minute and a half. The period of current has no appreciable effect on the movement of the minutes type-wheel, since the magnet *i* in attracting its armature permits only an infinitesimal progression of said type-wheel. As soon as the current 35 breaks the type-wheel moves ahead one step and continues to do so during the three-minute intervals, the hour type-wheel stepping ahead once for every complete rotation of the minute-wheel. During the escape of the pin-wheel *h*⁴ upon each break in the clock-current the fly *h*¹ and pallet *h*⁸ act as a retarder to prevent the parts from moving too suddenly. The figures on the type-wheels indicating the time are thus regularly changed; 40 but no imprint is made on the tape *T* unless an impulse is received through the printing-magnet *g*. Upon the receipt of such an impulse the said magnet will attract its armature, and the platen *e*² will be elevated and 45 will cause to be printed on the tape the figures on the type-wheels which are then opposite the platen. The cessation of the impulse in the printing-magnet causes the platen to descend.

50 I claim—

1. In a device of the character specified, the combination of a type-wheel, a mechanically-driven clock-train adapted to rotate said wheel, an escapement for said train, an elec- 55 tromagnet for operating said escapement, an electrical make-and-break device in circuit

with said magnet, and a time mechanism for operating said device.

2. In a device of the character specified, the combination of a type-wheel, a clock-train 65 adapted to rotate said wheel, a retarding-escapement included in said clock-train, a second escapement controlling said clock-train, an electromagnet for operating said second escapement, and a time mechanism control- 70 ling the circuit of said magnet.

3. In a device of the character specified, the combination of a type-wheel having a shaft, a second shaft geared to said type-wheel shaft, 75 a motive device for rotating said second shaft, an escape-wheel carried by the second shaft, a detent coöperating with said escape-wheel, an electromagnet for operating said detent, a second escape-wheel carried by said second shaft, and a pallet device coacting with said 80 second escape-wheel as a retarder, during the action of the magnet-operated escapement.

4. In a device of the character specified, the combination of a type-wheel, a clock-train adapted to rotate said wheel, a wheel rotated 85 by said clock-train and having a circular series of pins, a detent having stops movable into and out of the path of said pins, and successively engaging a pin to liberate the wheel one pin at a time, a retarder in the clock-train 90 adapted to retard its movement during the escape of the pin-wheel, an electromagnet having its armature connected with and adapted to operate said detent, and means for controlling the circuit of said magnet. 95

5. In a device of the character specified, the combination of a printing device, an electromagnet controlling the same, a pair of contact-posts or terminals for the winding of said magnet, a base carrying said parts, a clock, 100 an electrical make-and-break device mounted on the clock and operated by its mechanism, and contact-posts or terminals for said device mounted on the clock and separably connected with the posts on the base. 105

6. In a device of the character specified, the combination of a shaft, a type-wheel fixed thereto, a series of projections carried by said shaft and circularly arranged therearound, two ink-ribbon rolls provided with ratchets, a 110 pawl device for rotating said ratchets, a suitably-journalized arm carrying said device, and adapted to be intermittently engaged and oscillated by the said projections, and yielding means, adapted to retract said arm. 115

In testimony whereof I have affixed my signature in presence of two witnesses.

EDWARD DAVIS.
